[57] CLAIM

The ornamental design for a floppy disk drive for word processor system, as shown and described.

DESCRIPTION

FIG. 1 is a perspective view of a floppy disk drive for word processor system showing our new design;

FIG. 2 is a top plan view thereof;

FIG. 3 is a right side elevational view thereof, the left side being substantially identical thereto;

FIG. 4 is a front elevational view thereof;

FIG. 5 is a rear elevational view thereof;

The left side elevational view being substantially identical to the right side.

FIG. 1

FIG. 2

FIG. 3

FIG. 4

FIG. 5
